UNITED STATES PATENT OFFICE

133,620

DESIGN FOR A TYPEWRITING MACHINE

Russell G. Thompson, Elmira, N. Y., assignor to
Remington Rand Inc., Buffalo, N. Y., a corpora-
tion of Delaware

Application July 12, 1941, Serial No. 102,111

Term of patent 14 years

To all whom it may concern:

Be it known that I, Russell G. Thompson, a citizen of the United States, residing at Elmira, in the county of Chemung and State of New York, have invented a new, original, and ornamental Design for Typewriting Machines, of which the following is a specification, reference being had to the accompanying drawings forming part thereof.

Fig. 1 is a perspective view of a typewriting machine showing my new design.

Fig. 2 is a front elevational view of the same.
Fig. 3 is a side elevational view of the same.
Fig. 4 is a top plan view thereof.
The dominant features of my design are shown in solid lines in the drawings.

I claim:

The ornamental design for a typewriting ma-
chine, as shown and described.

RUSSELL G. THOMPSON.
